CARRIAGE

Sheldon Rutter, Miami, Fla., assignor to Thayer, Inc.,
Gardner, Mass., a corporation of Massachusetts

Filed Jan. 22, 1963, Ser. No. 73,273

Term of patent 14 years

(Cl. D14—14)

FIG. 1.

FIG. 2.

FIG. 1 is a perspective view of the carriage showing my design with a portion broken away for convenience of illustration, and

FIG. 2 is a view in rear elevation.

The dominant features of my design reside in the portions shown in full lines. The side not shown is substantially the same in appearance as the side shown.

I claim:

The ornamental design for a carriage, substantially as shown and described.
